GERHARD HOHN, OF GOSLAR-ON-THE-HARZ, GERMANY

SUSPENDERS FOR SOCKS OR THE LIKE ARTICLES OF HOSIERY

Application filed June 20, 1928, Serial No. 287,004, and in Germany February 25, 1928.

The present invention relates to suspenders for socks or the like articles of hosiery.

Suspenders for this purpose are already known in which a pad or the like support for the securing means is displaceable on the garter band.

The object of the invention is to so construct the displaceable pad of a single strip of leather or similar material that one portion of the strip will form a seat for the loop member of the fastener and another portion of the strip will enable to secure a band supporting the knob plate in such a manner as to render easy also the attachment of very long socks.

15 The seat for the loop member is formed by making one depending end of the pad longer than the other, and by bending this about itself so that the edge can be inserted between the opposite depending end and its own body portion and can then be secured thereto by stitching or the like means.

The knob plate in the improved sock suspender is secured to a long strip or band which in turn is inserted in a slot in the pad substantially adjacent the upper folded edge of this. It is therefore possible to lead the top edge of the stocking right up to the top edge nearly of the garter. Moreover, as no strain acts upon the knob plate, the separate support for the knob plate allows to use for this purpose a thin band and thus to avoid an onerous thickness of the suspender.

One form of construction of the invention is shown in the accompanying drawings in 35 which:—

Figure 1 is a front elevation of the sock suspender and

Figure 2 is a section on a larger scale along the line A—B in Figure 1.

40 A support or pad 1 of the sock suspender which is made, according to the invention, of a single piece, preferably of leather, is folded over the top edge of a garter 2, whilst the dependent end portions 3 and 4 are rigidly connected together substantially adjacent the bottom edge of the garter band for example by stitching. An eye 6 adapted to receive the loop member 5 of clip means for the sock is formed by an extended portion 7 of 45 one end portion 3. This extension 7 is

pushed between the ends of the support or pad and rigidly connected therewith by stitching.

In order to render easy the attachment of particularly long socks, a knob plate 8 of the 55 clip means is attached to a long strip or band 9 secured to the support or pad 1 near the upper folded edge thereof.

This attachment is carried out as shown in Figure 2 by forcing the free end of the strip 60 or band 9, acting as support for the knob plate 8, into a slot provided in the back portion 4 of the support before folding and stitching together the material used for the support, the end pushed through being itself 65 stitched to this portion of the pad.

I declare that what I claim is:—

A suspender for personal wear comprising in combination a garter band, a looped pad displaceable thereon, consisting of a single 70 strip of material folded over said garter band and having a pair of dependent portions of different length, the said dependent portions being secured together near the lower margin of said garter band, a button 75 and loop fastener, a fold formed in the longer dependent portion to form a seat for the loop member of the said fastener, means for securing together the free ends of the said dependent portions to close said seat, the rear wall 80 of the said pad having a slot, a thin band carrying the button plate of the said fastener and having its upper end inserted into the said slot and secured to the inner side of the rear wall of the pad.

In testimony whereof, I have signed my name to this specification at Frankfort-on-the-Main, Germany, this 25th day of May, 1928.
